UNITED STATES PATENT OFFICE

GEORGE R. BENNETT, OF SOUTH MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

INSULATOR-SUPPORTING FIXTURE

Application filed July 12, 1926. Serial No. 121,868.

This invention relates to certain new and useful improvements in insulator supporting fixtures and refers more particularly to what is generally termed in the art as a secondary rack employed for carrying secondary wires along poles and other places.

In the production of supporting fixtures of the character described, it is of utmost importance that they be of sufficient strength to withstand all stresses, at the same time being capable of economical production to compete with the market and this invention has as an object to generally improve and simplify the construction of secondary racks whereby the same have a large factor of safety to withstand all stresses and at the same time may be readily manufactured at a low cost.

A further object of this invention resides in the provision of an improved insulator carrying rack adapted to be formed from a blank by folding the same medially upon itself to define a laterally projecting flange which is divided into a plurality of spaced bracket arms.

And a still further object of this invention resides in the provision of an improved rack of the character described which is preferably stamped from a one-piece blank and which is of rigid and substantial construction.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view of an insulator supporting rack or supporting fixture embodying my invention, and

Figure 2 is a view, partly in section and partly in elevation, taken through Figure 1 on the plane of the line 2—2.

The improved fixture is formed from a single blank 5 having medial, transversely extending, recesses defining transverse strips or straps 6 forming laterally projecting spaced bracket arms 7 when the blank is folded longitudinally upon itself along a central line. The cut-away or recessed portions have tongue portions 8 extended thereinto from one end and flanges 9 extending thereinto from the sides. In the finished structure, the tongue portions 8 are bent to form ties with their free ends directed inwardly and riveted or otherwise secured, as at 10, to the other half or section of the blank to prevent spreading. The flanges 9 are directed inwardly and adjacent flanges abut, as illustrated in the drawing, to reinforce the bracket arms and close the top and bottom portions thereof.

The longitudinal marginal edge portions of the blank are flanged laterally to form attaching flanges 11 provided with apertures 12 for receiving lag screws or other means 13 for securing the fixture to a suitable support, indicated as at 14.

Pin receiving apertures 15 are formed in the outer ends of the bracket arms, by the fold of the blank to receive a mounting pin 16 which passes through the apertures and through insulating spools 17 inserted in the space between adjacent bracket arms, the flanges 9 retaining the mounting pin at the fold of the blank as will be readily apparent.

It will thus be apparent that comparatively thin sheet stock may be employed in the formation of my improved fixture without the sacrifice of strength, as the flanges 9 provide ample reinforcement for the bracket arms which are substantially rectangular shape in cross section, being formed in two channeled sections having the edges of their side flanges abutting, and that the base of the fixture is strongly reinforced by the ties 8, thus producing a very economical, strong and practical fixture.

What I claim as my invention is:

1. An insulator supporting fixture inte-

grally formed from a single blank of bendable metal, comprising a plurality of bracket arms folded upon themselves at their outer ends, the fold of the material dividing the fixture substantially into complementary sections and forming aligned pin receiving apertures at the outer end of the bracket arms, attaching flanges at the base of the bracket arms for securing the fixture to a support, 10 and a tongue connecting the complementary sections of the fixture between adjacent bracket arms.

2. An insulator supporting fixture integrally formed from a single blank of bendable metal, comprising a plurality of bracket arms folded upon themselves at their outer ends, the fold of the material of said outer ends forming aligned pin receiving apertures, inwardly directed marginal flanges on the 20 edges of the arms whereby the halves of the bracket arms are substantially channel shaped to reinforce the same, an integral tongue part projecting from one side of the fixture between the bracket arms, means securing the 25 free end of the tongue part with the other side of the fixture whereby the halves of the bracket arms are held against spreading, and lateral attaching flanges at the marginal edges of the fixture for securing the same to a support.

3. An insulator supporting fixture integrally formed from a single piece of bendable metal, comprising spaced substantially U shaped arms whose closed ends are adapted to 35 receive an insulator mounting pin, the sides of the U shaped arms on each side of the fixture forming continuations of each other at their base, a tongue extended from the continuation of the arms at one side, means securing 40 the free end of said tongue with the continuation of the arms at the other side to prevent spreading of the sides of the U shaped arms, and attaching flanges at the base of the arms for securing the fixture to a support.

45 In testimony whereof I affix my signature.
GEORGE R. BENNETT.
